KEYBOARD PERFORATOR AND COUNTER

William H. Eddy, Downers Grove, Ill., assignor, by
mesne assignments, to Teletypesetter Corpora-
tion, a corporation of Delaware

Application December 20, 1937, Serial No. 180,758

7 Claims. (Cl. 164—112)

This invention relates to improvements in composing systems and apparatus therefor and particularly to perforators and counters which may be utilized for preparing a perforated strip for the automatic control of composing machines.

The principal object of the present invention is to provide means for restricting the cooperation between a reciprocating instrumentality and a periodically actuated mechanism to response to certain operating conditions.

Another is to render the operation of the justification indicator of a keyboard perforator and counter more accurate and reliable by eliminating undesirable operating conditions.

Specifically, in prior keyboard perforators and counters, the pawl which operates the justification or space band pointers, oscillates with its control lever during the operating cycle of the bar on which both the pawl and the control lever are mounted. This oscillation, at the high speed encountered during the operation of the perforator and counter, tends to cause said pawl to overtravel and occasionally to engage the justification pointer spacing rack or ratchet prematurely, thus interfering with the complete return of the space band pointers to their starting or beginning of line position, or causing false space band indications to occur. With the feature of the present invention, greater operating margins are provided because thereby the spacer feed pawl is held out of contactual engagement with its control lever at all times except during a cycle of operation of the space band indicating mechanism.

A better understanding of the foregoing and other objects of the present invention may be had from the following description, taken in conjunction with the accompanying drawing wherein like reference characters represent similar parts throughout the several views.

Fig. 1 is a perspective view of a perforator and counter with parts broken away showing the apparatus necessary for a clear understanding of the present invention;

Fig. 2 is a fragmentary front elevational view of the apparatus illustrated in Fig. 1 to show more clearly the improvement according to the present invention;

Fig. 3 is a perspective view of the counting stop unit per se; and

Fig. 4 is a fragmental sectional view of the selector mechanism.

The feature according to the present invention is disclosed in the present embodiment in connection with the keyboard perforator and counter

covered in U. S. Patent No. 2,059,250 granted November 3, 1936, to H. L. Krum. Having reference to Figs. 1, 2, 3, and 4, it is noted that most of the parts shown have their counterpart in the structure illustrated in said patent, the entire perforating mechanism not being shown but which is nevertheless considered as operatively associated with the present invention. In Fig. 1, a plurality of key levers 11 are pivoted on a common rod (not shown) and are normally urged upwardly by individual springs, as is common practice. These key levers extend over a selector mechanism (not shown) comprising a number of pairs of selector bars for controlling the perforator unit, indicated generally by the numeral 12, and over the similar pairs of bars 13 and 14 (Fig. 4) included in a selecting unit for controlling the counting mechanism, indicated generally by the numeral 15. The key levers 11 are each provided with a key 16 individual thereto. The bars 13 and 14 of each pair are supported by a pair of T-shaped rocker members 17 disposed at each end of the pairs of bars 13 and 14, the rocker member at only one end of the selector bars being shown in Fig. 4. Each series of selector bars 17 is mounted on a pivot rod 18 and have oppositely directed lugs 19 and 21, which support the selector bars 13 and 14, respectively, of the corresponding pair of bars. The rocker members 17 of each pair of selector bars 13 and 14 are pivoted to and reciprocate a permutation bar 22, each of which is pivotally articulated to a Y-shaped selector lever 23 pivoted on a rod 24. The permutation bars 22, indicated in Fig. 4, are those provided for the control of the counting mechanism. Similar permutation bars (not shown) are provided for the control of the perforator 12, and are pivoted to individual levers 25 (Fig. 1), each of which, in turn, reciprocates a punch interference member 26 individual thereto.

Each key lever 11 is arranged to depress one or the other of each pair of selector bars 13 and 14, and through the medium of the rocker members 17, lifts the other selector bar of the pair either to advance or retract the associated permutation bar 22 to impart corresponding movement to the associated Y-shaped lever 23. Upon depression of a key lever, the permutation bars 22 are set in characteristic combinations. As set forth in Patent No. 2,059,250, each key lever 11, in addition to actuating the selector bars 13 and 14, also operates a universal bar (not shown) which functions to initiate a cyclic operation of the apparatus by tripping the clutch mechanism, indi- 55

cated generally as 20 (Fig. 1), associated with the operating shaft 29. Shaft 29 also carries a series of cams adapted to carry out the several operations of the apparatus. For instance, a cam 50 is employed to operate the perforator 12, and a cam 60 is provided to operate the spacing bar 69. Bar 69 carries mechanism, indicated generally (in Fig. 1) as 10, for controlling the operation of an adjustable space band mechanism, indicated generally as 70 (and disclosed in U. S. Patent No. 2,083,608 issued June 15, 1937, to E. S. Larson), to actuate a pair of space band pointers 64 and 65.

The setting of the Y-shaped levers 23 permutations upon the depression of a key lever 11 will control the setting of a plurality of notched discs 31 (Fig. 3), forming part of the counting mechanism 15. Individual to each of the levers 23 and notched discs 31 is a transfer lever 32 pivotally mounted on a rod 33 secured to a bracket 30 (Fig. 4) which is actuated by a cam (not shown) carried on the operating shaft, as fully set forth in Patent No. 2,059,250. For each operation of bracket 30, the transfer levers 32 will be moved downwardly (as viewed in Fig. 4) into operative relation with the Y-shaped levers 23; that is, whether the levers 23 are set in their counterclockwise or clockwise positions, the depending arms of transfer levers 32 will engage or be free of corresponding upper ends of the arms of Y-shaped levers 23 to cause the discs 31, upon actuation of bracket 30, to be rotated slightly in either a counterclockwise or clockwise direction respectively. With the Y-shaped levers 23 operated in varying permutations in accordance with the movement of the permutation bars 22, the discs 31 will likewise be rotated in varying combinations and will correspondingly cause for each setting thereof an alignment of the notches in the periphery of the discs 31.

Cooperating with the notches in the discs 31 are a plurality of rods 34, there being a rod individual to each set of notches (when aligned), and each rod is arranged with anti-friction rollers 35. Each of the rods 34 is centripetally biased by an individual spring 36. In this manner, the rods 34 normally tend to move radially toward a common center into the notches of the discs 31, but inasmuch as the notches of the discs 31 are arranged so that for each setting of the discs only one group of notches will be in transverse alignment, only one of the rods 34 at a time will be moved into the notches. Also, the notches in the discs 34 are arranged so that when the discs are moved for a subsequent selection, the previously selected rod 34 will be cammed outwardly against the action of its associated spring 36. Operatively secured to the right-hand end of each of the rods 34 is a stop member 37 (Fig. 3) which slides in suitable slots formed in a circular member 38.

To the right of the code disc selector 39 (as viewed in Fig. 3) is a counting barrel or unit 41, forming a part of the counting mechanism, which is rotated by power communicated from a continuously rotating motor 40 through a friction clutch 42. The counting unit 41 comprises a plurality of circumferentially arranged slides 43 which are longitudinally slideable and coat with the stop members 37 to determine the degree of rotation of unit 41, and any of the slides 43 which are found in the zero position are operated invariably by a lever 27 (corresponding to lever 205 disclosed in Patent No. 2,059,250), controlled by a cam (not shown) carried on the operating

shaft 29. Simultaneously with the actuation of a slide in its zero position, the previously operated slide is restored to its normal or non-operating position by a collar 44 to accomplish, through the coaction of an operated slide 43 and a selected stop member 37, the incremental progressive movement of the counting unit 41. The counting unit 41 includes a shaft 45 on which is formed a worm 46.

As previously mentioned, the slides 43 cooperate with the members 37 to control the rotation of the counting unit 41, which is driven through the friction clutch 42, to cause a corresponding degree of rotation to worm 46. The rotation of worm 46, which meshes with a gear 47 secured to a shaft 48, causes the corresponding or proportional angular rotation of a shaft 49 through gears 51 and 52. A worm 53 is fixed to the right extremity (as viewed in Fig. 1) of shaft 49 and meshes with a worm wheel 54 associated with the counting clutch arrangement indicated generally as 28, completing a gear train between the counting unit 41 and counting clutch 28.

As shown in Fig. 1, the indicator comprises a portion 55 of sectoral shape mounted on a frame 56 carried on the base 57, which portion carries slidably thereon a dial or scale 58 provided adjacent its arcuate edge with a scale or series of graduations representing the number of units in a line of maximum length. Associated with the scale 58 is a matrix pointer 59, the reverted end of which moves along the arcuate edge of the dial from left to right, towards zero, in response to the totalization of the matrix thicknesses by the counting mechanism 15. Thus, the distance from the pointer 59 to zero indicates the amount of space left in the line to be filled with matrices when the line contains no space bands. However, when space bands are inserted in the line, the space remaining to be filled varies with the number of space bands inserted. So, to indicate the justifiability of the line being composed, the pair of space band pointers 64 and 65 is provided, the distance between the pointers 64 and 65, when in the dotted line position, for example, indicating the amount of expansibility of the space bands.

In the embodiment shown, the dial 58 is articulated to the minimum space band pointer 65 through pin 61 and is movable with said pointer. The space left in the line to be filled with matrices is represented by the distance between the matrix pointer 59 and any point between space band pointers 64 and 65. The manner of effecting the differential or proportional movement of pointers 64 and 65 toward the left (from the zero position) is fully set forth in Patent No. 2,083,608 and will be described only briefly hereinafter. The matrix pointer 59 is disposed between a flanged sleeve 62 (which carries gear 54) and a disc 63, and, as fully described in the aforementioned patents, the matrix pointer 59 is rendered movable with the gear 54 by reason of the pressure produced between it and the disc 63 by a spring 66 through rod 67. To effect the return of the matrix pointer 59 leftwardly to its initial or beginning of line position against a stop (not shown), the rod 67 integrally formed with disc 63 is pushed forwardly by a suitable means against the compressive action of spring 66 to relieve said pressure and permit the matrix pointer 59 to be returned to its initial position by a spring 68 acting on a cord 71.

As previously mentioned, the adjustable space band mechanism 70 is fully described in U. S. 75

Patent 2,083,608 and provides means for varying the incremental movements of space band pointers 64 and 65 independently of each other. Briefly, to accomplish this result, there are 5 mounted on a bracket 72 two adjusting screws 73 and 74 (Fig. 2) which control the movement of traveling blocks 75 and 76. Carried on fulcrums 77 and 78 integral with blocks 75 and 76 are operating levers 79 and 81. Through the 10 rotation of screws 73 and 74 the blocks 75 and 76 are caused to travel therealong, thus varying the position of fulcrums 77 and 78 to change the rotative movements of levers 79 and 81, respectively.

15 Movement is imparted to levers 79 and 81 mechanically through the operation of spacing bar 69 in the manner fully described in Patent No. 2,083,608 but will be briefly described here to clarify the present description. Spacing bar 20 69 is pivotally articulated to a lever 82 (Fig. 1) suitably carried on a pivot (not shown) mounted in a bracket carried on base 57, which lever carries a follower roller that cooperates with cam 60. For each half revolution of cam 60, spacing bar 25 69 is reciprocated leftwardly and then returned to its normal rightward position. Carried on spacing bar 69 near its right-hand end is a lever 83 which has latching relation with an intermediate lever 84, also pivotally carried on spacing bar 69. Intermediate lever 84 cooperates with a spacing pawl 85 so that, when space key lever 86 is depressed, link 87 pivoted thereto is actuated downwardly to impart clockwise rotation to lever 83 to cause the disengagement of lever 83 from 30 the intermediate lever 84. Thus disengaged, lever 84 is actuated in a clockwise direction by a spring 88 to throw spacing pawl 85 into engagement with a spacing rack 89 carried on a movable bracket 91.

40 Spacing pawl 85 is biased normally in a counterclockwise direction by a spring 92 against an adjustable stop member 93. Stop member 93, as shown in Fig. 2, is of the eccentric screw type and is secured to the spacing bar 69, adjustment being effected by the hexagon flange 94 integral therewith. In this manner, spacing pawl 85 normally bears against the stop 93 instead of against the intermediate lever 84. Spacing pawl 85 is thereby rendered independent of the hereinafter described vibrations imparted to intermediate lever 84 by the reciprocating action of spacing bar 69. Upon the operation of space key lever 86, lever 84 will be oscillated once due to the tripping action imparted by lever 83 and the restoration action imparted to intermediate lever 84 by plate 95 through depending lug 96; that is, intermediate lever 84 becomes unlatched from lever 83 substantially simultaneously with the tripping of the clutch 20; therefore, as cam 60 rotates to operate lever 82 to move spacing bar 69 leftwardly, intermediate lever 84 has already been tripped in readiness for this action, and spring 88 has urged lever 84 clockwise against spacing pawl 85 to raise the spacing pawl 85 into engagement with spacing ratchet 89. Then, as spacing bar 69 is actuated leftwardly, pawl 85 carries the ratchet 89 in the same direction until depending lug 96 of intermediate lever 84 strikes against reset plate 95, whereupon counterclockwise rotation is imparted to lever 84 against the tension of spring 88 to bring lever 84 again into latching engagement with lever 83. Spacing pawl 85 is thereupon disengaged from ratchet rack 89 by its spring 92 and brought against the adjustable stop 93. The ratchet rack 89 is retained 50

55

60

65

70

75

in its actuated position by a retaining pawl (not shown).

As disclosed in Patent No. 2,059,250, the spacing bar 69 is reciprocated upon the depression of every key lever, although it becomes effective to move the spacing rack only upon the depression of the space key lever. Therefore, it is apparent that for every reciprocation of spacing bar 69, the depending lug 96 of lever 84 will strike against plate 95, because to enable the latching of levers 10 83 and 84, lever 84 must be rotated counterclockwise a sufficient distance (that is, lever 84 must be given a slight amount of overtravel) to effect its latching engagement with lever 83, thereby causing, in response to every key operation, momentary vibration of intermediate lever 84. This sharp, but momentary, action on lever 84 was transferred to the spacing pawl 85, since heretofore the spacing pawl 85 normally rested upon the leftwardly extending arm of lever 84. This caused 20 the spacing pawl 85 to engage the rack 89 accidentally and occasionally resulted in false operations of the space band indicating mechanism. To obviate this difficulty, the adjustable stop 93 was provided for spacing pawl 85, thereby rendering spacing pawl 85 normally independent of intermediate lever 84; that is, during all operations except that in response to the operation of the space key.

Having reference to Fig. 2, lever 79 (as more 30 fully described in Patent No. 2,083,608) is pivotally connected at its upper end to a gear rack 97, and lever 81 is pivotally connected to a gear rack 98. The lower end of operating lever 79 is provided with an open ended slot which cooperates with a pin 99 secured to frame 91. Similarly, operating lever 81 is also provided with an open ended slot at its lower end which cooperates with a pin 101 also secured to frame 91, so that upon actuation of spacing rack or ratchet 89 by the pawl 40 85, this movement is imparted to frame 91 and, in turn, causes levers 79 and 81 to rotate about their fulcrums 77 and 78, respectively, thus imparting movement to gear racks 97 and 98. Gear rack 97 meshes with a gear sector 102 associated with the maximum space band pointer 64, and similarly, gear rack 98 meshes with a gear sector 103 associated with the minimum space band pointer 65. Thus, upon actuation of the gear racks 97 and 98 through the instrumentality of spacing ratchet 45 89, the space band pointers 64 and 65 are moved differentially or proportionately for each reciprocation of spacing bar 69 (and hence spacing ratchet 89) in response to each operation of space pawl 85, the relative movements being dependent 50 upon the adjustable position of fulcrums 77 and 78.

It is understood that various changes may be made in the details set forth in the foregoing description without departing from essentials of 60 the invention or from the spirit or the scope of equivalency thereof, as defined by the appended claims.

What is claimed is:

1. In a keyboard apparatus for producing control strips for composing machines, a series of 65 keys, means adapted to be reciprocated invariably upon the actuation of said keys, a periodically actuated mechanism cooperably related to said means, and eccentric means effective on said means to vary the cooperative relationship between said means and said mechanism.

2. In a keyboard apparatus for producing control strips for composing machines, a series of 70 keys, a reciprocating instrumentality invariably 75

- operated in response to said keys, a periodically actuated mechanism cooperably related to said instrumentality, and eccentric means effective on said instrumentality to vary the cooperative relationship between said instrumentality and said mechanism.
3. In a keyboard apparatus for producing control strips for composing machines, a series of keys, a reciprocating instrumentality invariably actuated in response to said keys, a periodically actuated mechanism cooperably related to said instrumentality, and eccentric means effective on said instrumentality to restrict the cooperation between said instrumentality and said mechanism to response to a certain one of said keys.
4. In a keyboard apparatus suitable for the production of perforated tape representing lines of composition, a series of keys, a scale, a pointer movable variably with respect to said scale to indicate a condition representing cumulative widths of characters, a pair of pointers, a special key, means adapted to be reciprocated invariably upon the actuation of said keys, supplemental means carried by said means and rendered operative by said special key, differential gearing operable by said supplemental means for rotating said pair of pointers different amounts for each effectiveness thereof for indicating a different condition, and means to vary the cooperative relationship between said supplemental means and said gearing.
5. In a keyboard apparatus suitable for the production of perforated tape representing lines of composition, a series of keys, a scale, a pointer movable variably with respect to said scale to indicate a condition representing cumulative widths of characters, a pair of pointers, a special key, means adapted to be reciprocated invariably upon the actuation of said keys, supplemental means carried by said means and rendered operative by said special key, differential gearing operable by said supplemental means for rotating said pair of pointers different amounts for each effectiveness thereof for indicating a different condition, and eccentric means effective on said

supplemental means to restrict the cooperation between said supplemental means and said gearing to response to certain operating conditions.

6. In combination with a keyboard apparatus suitable for the production of perforated tape representative of consecutive characters and word spacers, a series of keys, a scale, a pointer movable variably with respect to said scale in response to the operation of said keys to indicate the cumulative widths of characters, a pair of pointers, means for operating said pair of pointers differentially to indicate the cumulative expansibility of the word spacers, a special key, means reciprocated invariably upon the operation of said keys, supplemental means carried by said reciprocable means cooperable with said first recited means, said special key when actuated adapted to render said supplemental means operative to actuate said pointers to correspond to the increment of expansibility provided by a spacer, and eccentric means effective on said supplemental means to restrict the cooperation of said supplemental means with said first recited means to response to said special key only.

7. In a keyboard apparatus suitable for the production of perforated tape representing lines of composition, a plurality of keys, a counting device, means to operate said device incrementally according to the keys depressed, an indicator dial, an index hand, said index hand operable variably with respect to said dial to correspond with the operation of said device, a special key, a pair of pointers, differential means for actuating said pointers, means adapted to be reciprocated invariably upon the actuation of each of said keys, means carried by said reciprocable means and cooperable with said differential means upon the actuation of said special key, and means to vary the cooperative relationship between said last recited means and said differential means, the relative actuation of said index hand and said pointers indicating at all times the justifiability of the line being composed.

WILLIAM H. EDDY. 45
